TURNING MACHINE

Otis E. Staples, Euclid, Ohio, assignor to The Cleveland Hobbing Machine Company, Cleveland, Ohio, a corporation of Ohio

Application February 28, 1941, Serial No. 381,035

6 Claims. (Cl. 82—13)

The present invention relates to machines for working metal, plastics, wood, and the like, and more particularly to machines for turning material in a manner analogous to that disclosed in copending applications of Theodore F. Carlin, Serial Nos. 242,703 and 249,940, filed November 28, 1938, and January 9, 1939, now Patents Nos. 2,233,398 and 2,233,399, respectively, issued March 4, 1941. In some respects the present invention may be considered an improvement on the machines disclosed in said applications.

The principal object of the present invention is the provision of a novel improved machine for working metal, plastics, wood, and the like which will be rugged in construction and reliable in operation, and which has a high production and wherein the operation taking place is performed at or near maximum speed consistent with the material being worked and the tool employed.

The present invention resides in certain details of construction and combinations and arrangements of parts, and further objects and advantages of the invention will be apparent to those skilled in the art to which the invention relates from the following description of the preferred embodiment thereof described with reference to the accompanying drawings forming a part of the specification and in which

Fig. 1 is a perspective view of a machine embodying the present invention showing the front and left-hand side of the same as viewed from the front;

Fig. 2 is a perspective view of the machine shown in Fig. 1 showing the front and right-hand side of the machine;

Fig. 3 is a vertical sectional view with portions in elevation taken approximately through the center line of the machine;

Fig. 4 is a sectional view with portions in elevation approximately on the line 4—4 of Fig. 3;

Fig. 5 is an enlarged view of a portion of the right-hand side of the machine;

Fig. 6 is a vertical sectional view with portions in elevation, taken approximately on the line 6—6 of Fig. 5;

Fig. 7 is a horizontal sectional view with portions in elevation taken approximately on the line 7—7 of Fig. 8;

Fig. 8 is an enlarged view taken approximately on the line 8—8 of Fig. 7;

Fig. 9 is a sectional view with portions in elevation taken approximately on the line 9—9 of Fig. 7; and

Fig. 10 is a wiring diagram of the electric circuits of the machine.

While the invention is susceptible of embodi-

ment in various modifications and alternative constructions, it is herein shown and described as embodied in a vertical turning machine wherein the work is rotated about a vertical axis in cutting relation with a disk-like, face-type tool rotated about an axis at right angles to the axis of rotation of the work, while a relative feed movement is effected between the blank and cutter in a direction longitudinally of the axis of rotation of the work. The cutter has portions of different radii adapted to turn different diameters on the work blank, and the speed of rotation of the work blank is varied as the respective portions of the cutter engage the blank so that the cutting operation is always performed at the maximum cutting speed consistent with other requirements, thereby obtaining maximum production.

Referring to the drawings, the machine shown therein is of the vertical type and comprises a base A which forms a support for a vertical hollow column B which in turn supports a number of machine tool elements including a work head C slidably supported for vertical movement on two pairs of vertically spaced ways 10 and 11 on the column B, and a tool head D adjustably supported for movement in a horizontal plane in a cylindrical aperture 12 intermediate the ways 10 and 11. The work blank W is supported by a suitable chuck 14 fixed to the upper end of a vertical work spindle or machine tool element 15 and a center 16 carried by a suitable tailstock 17 slidably supported on vertical ways 18 and 19 formed on the side of a work head C. The tailstock 17 is adapted to be moved vertically and clamped and unclamped with respect to the ways 18 and 19 by a single operating lever 20.

The tool T which is semi disk-like in shape is carried by a horizontal tool spindle or machine tool element 21 rotatably supported in a tool head 40 D and during the cutting operation is slowly rotated about its axis as the work is fed vertically past the same. In the present instance the tool T is adapted to turn a piece of work having four different diameters, 1, 2, 3 and 4, and accordingly 45 the tool has four arcuate cutting portions a, b, c, and d, each of different radius. In order to obtain maximum production from the machine, the work spindle 15 is driven by a multiple speed electric motor 22, see Fig. 3, hereinafter referred to as the cut motor, the speeds of which are so adjusted that maximum cutting speed in feet per minute consistent with other conditions, such as, the character of material being turned, the kind of tool employed, the rate of feed, etc., is maintained irrespective of which portion of the work

blank is being turned. As shown, the vertical feed movement of the work head C which effects the feed is produced by a cooperating lead screw 23 and nut 24, the former of which is driven from the work spindle. A high speed reversible electric motor 30, hereinafter referred to as the rapid-traverse motor, operatively connected to the nut 24 provides means for rapidly moving the work head C to bring the work up to the tool at the beginning of the cycle of operations of the machine and for returning the work head to its starting position after the blank has been turned and removed.

The machine is started by pressing a start button 31, as will be hereinafter fully described, which closes a circuit to the rapid-traverse motor 30 causing the same to rotate the nut 24 to move the work head upwardly at a rapid rate. Just prior to the engagement of the work with the tool, an adjustable stop 32 carried on a bar 33 fixed to the top of the work head C actuates a switch 34, stopping the rapid-traverse motor 30 and starting the cut motor 22. Thereafter the work head C continues to move in an upward direction but at a feed rate, and as the different diameters of the work reach cutting position, the speed of the motor 22, which motor has a limited number of definite speeds as distinguished from a variable speed electric motor having an infinite number of speeds, is automatically changed by a plurality of adjustable stops 35, 36, 37, and 38 carried by a plate 39 fixed to the work head C. These stops actuate suitable electric speed selection switches 40, 41, 42 and 43 fixed to the upper part of the column B and connected in the control circuit in a manner hereinafter described.

After the cutting operation is completed the circuit to the cut motor 22 is opened upon the actuation of a travel limit switch 44 by an adjustable stop 45 on the bar 33, whereupon the machine stops. When the start button 31 is again depressed after the blank is removed, the rapid-traverse motor 30 operates in the reverse direction to return the work head C to starting position. In order to increase the flexibility of the machine the control for the cut motor 22 preferably comprises a drum controller, designated generally by the reference character E, through the medium of which control circuits for the motor can be so selected that the motor will go through its cycle of various speeds automatically or any one of its various speeds can be selected. In the latter event the selected speed alone will operate during the entire cutting operation. In addition to the automatic position, designated "auto," and the four different speed positions, designated 1, 2, 3, and 4, the drum controller E also has an off position, designated "off."

Referring to the specific construction of the machine shown, the work spindle 15 is rotatably supported by anti-friction bearings in the work head C and is driven from the cut motor 22 which is located within the column B but is fixed to and carried by the work head C through the medium of a bracket 46. The armature shaft 47 of the motor 22 is connected to a short shaft 48 by a coupling 49 of conventional construction. The shaft 48 is rotatably supported in the work head C and has a small gear 50 fixed thereon which is continuously in mesh with a large gear 51 fixed to a shaft 52 also rotatably supported in the work head C and which projects into a gear compartment 53 in the lower front part of the work head C. The shaft 52 is operatively connected to a short shaft 54 through the medium of gears 55

and 56 located within the gear compartment and fixed to the shafts 52 and 54, respectively. The shaft 54 is rotatably supported in the work head C and is provided at the left-hand end, as viewed in Figs. 3 and 4, with a bevel gear 57 continuously in mesh with the bevel gear 58 fixed to the work spindle 15. The gear compartment 53 is adapted to be closed by a removable cover 59, and the gears therein are preferably operated in oil.

The lead screw 23 is rotatably supported in the work head C against axial movement relative thereto and is rotated at a relatively slow speed and in timed relation to the rotation of the work spindle 15 to effect the feed movement of the work head C by the cut motor 22 to which it is operatively connected by a worm wheel 60 fixed to its upper end, which worm wheel is continuously in mesh with a worm 61 keyed on a horizontal shaft 62 rotatably supported in the work head C. The shaft 62, like the shaft 52, projects through the partition 63 in the work head C which forms the gear compartment 53, and the left-hand end thereof, see Fig. 4, is provided with a gear 64 in mesh with a gear 65 fixed to the shaft 54 to the left of the gear 56.

As previously stated, the nut 24 with which the lead screw 23 cooperates is adapted to be rotated at a high rate of speed to produce a rapid-traverse movement of the work head C in either direction by the rapid-traverse motor 30 which is supported on the bed A within the column B. The armature shaft 66 of the motor 30 is connected by a coupler 67 to a short shaft 68 rotatably supported in a bracket 69 which supports the nut 24. The shaft 68 is provided with a worm, not shown, continuously in mesh with a worm wheel 71 formed about the circumference of the nut 24. The lead screw 23 is preferably provided with a telescopic guard, designated generally as 72, which prevents the entrance of chips, etc., into the interior of the bracket 69.

The tool spindle 21 is rotatably supported in a cylindrically-shaped tool head D slidably but non-rotatably secured in the aperture 12 in the column B intermediate the ways 10 and 11. The tool head is adapted to be adjusted towards and from the axis of rotation of the work spindle 15 by a lead screw 75 rotatably supported in the column B and continuously in mesh with a suitable nut 76 fixed to the cylindrical rear end of the tool head. The lead screw 75 is provided with a micrometer dial 77 at the front end thereof which end projects through the column B. The tool head is adapted to be clamped in any position to which it is adjusted by a pair of movable clamps 80 and 81 positioned in a suitable aperture formed in the column B and adapted to be moved towards each other so as to clamp the cylindrical shank of the tool head D by a threaded shaft 82 projecting through the clamp member 80 and having threaded engagement with the clamp member 81. The shaft 82 projects to the outside of the column B and the projecting end thereof is formed with a driving connection to facilitate rotation thereof.

As the work head C moves vertically the tool spindle 21, and, in turn, the tool or cutter T are rotated slowly at varying rates of speed depending upon the radius of the particular cutting edge of the tool in contact with the work blank at any time, etc. As shown, the rotation of the tool is effected by a cam plate 85 bolted or otherwise suitably detachably connected to the work head

C, which cam plate has a cam slot 85 formed therein and within which a cam roller 87 engages. The cam roller 87 is adjustably fixed to a rack bar 88 slidably supported in an extension 89 of the tool head D. The rack teeth 90 of the rack bar 88 are continuously in mesh with a gear 91 fixed to the lower end of the tool spindle 21, as viewed in Fig. 7. To provide an adjustment between the roller 87 and the rack bar 88, the roller is mounted on a short shaft 92 fixed in a movable block or member 93 slidably supported in a suitable aperture 94 formed in a rack bar 88. The block or member 93 is adapted to be moved relative to the rack bar 88 by a screw 95 having threaded engagement with the member 93 and rotatably supported against axial movement in the rack bar 88. A driving connection on the projecting end of the screw 95 provides means for rotating the same and in turn adjusting the roller 87 with respect to the cutter. In order to eliminate back-lash in the mechanism operatively connecting the tool spindle 21 to the cam plate 85, the tool spindle is continuously urged in a clockwise direction, as viewed in Fig. 8 by an air motor 100 located within the column B, the piston rod 101 of which motor is connected by a sprocket chain 102 to a sprocket wheel 103 fixed to the tool spindle 21. The air motor 100 is continuously supplied with air under pressure during the operation of the machine.

The cut motor 22 shown is of the four-speed alternating current type which allows the spindle to be rotated at any of four different speeds, thus producing a machine which will accommodate the turning of pieces of work having four or less different diameters thereon with the cutting operation always being performed at maximum efficiency. It is to be understood, however, that a motor having any desired number of speeds can be employed. The type of motor selected will depend upon the particular article to be turned. A four-speed motor is selected in the present instance because four speeds are sufficient to accommodate most articles which the machine shown is designed to turn. In the event that it is desired to turn an article having more than four different diameters on the machine shown, two of the diameters which most nearly approach each other in size can be turned at the same speed or the shortest diameter can be turned at one of the four speeds which is most appropriate.

The relative positions of the various parts of the machine at the commencement of a cycle of operations is shown in Fig. 1. As shown in this figure the work head is at the bottom of its travel and a work blank has been positioned in the work head. The machine is started by depressing the start push button switch 31 located on a control panel 104 fixed to the left-hand side of the machine in a position readily accessible to the operator. With the drum controller E set at "auto," the depressing of the start push button switch 31 closes a circuit from line L-1 through normally closed stop push button switch 105, line 106, normally open start push button switch 31, line 107, operating solenoid 108 of relay 109, line 110, contacts 111 of a travel limit switch 44, line 112, overload contacts 96, line 97, overload contacts 88, line 99, overload contacts 113, line 114, overload contacts 115, line 116, overload contacts 117, line 118, overload contacts 119, to L-3. The overload contacts 96, 95, 113, 115, 117 and 119 are located on motor control panels, hereinafter referred to. The particular motor control panel

upon which these overload contacts are positioned is shown in the wiring drawing.

Energization of the operating solenoid 108 of relay 109 closes the normally open contacts 120, 121 and 122 thereof and opens the normally closed contacts 123 thereof. The closing of the contacts 120 of relay 109 establishes a circuit from the line L-1 through the normally closed stop push button switch 105, line 106, contacts 120, line 124, operating solenoid 125 of rapid-traverse motor control panel 126, line 127, closed contacts 128 of change-over switch 34, line 110, closed contacts 131 of travel limit switch 44, line 112, etc., to L-3. Energization of operating solenoid 125 of rapid-traverse motor control panel 126 closes the normally open contacts 130, 131 and 132, connecting the rapid-traverse motor 30 to the power lines L-1, L-2 and L-3 in such a manner that the motor is operated in a direction to rapidly raise the work head C.

Simultaneously with the closing of contacts 130, 131 and 132 of the rapid-traverse motor control panel 126, normally open contacts 133 on the same panel are closed. These contacts are in parallel circuit with the contacts 120 of relay 109 and establish a holding circuit for the operating solenoid 125 continuing the operation of the rapid-traverse motor 30 after the start push button switch 31 is released. The closing of the contacts 121 of relay 109 establishes a circuit from the line L-1 through the stop push button switch 105, line 106, contact bar 135 of drum controller E, line 136, contacts 121, line 137, operating solenoid 138 of relay 139, line 110, closed contacts 111 of travel limit switch 44, line 112, etc., to L-3. Energization of the operating solenoid 138 of relay 139 closes the normally open contacts 140 and 141 thereof. The contacts 140 are in parallel circuit with the contacts 121 of relay 109 and the closing of these contacts establishes a holding circuit for the operating solenoid 138 of relay 139 maintaining the solenoid energized after the start push button switch 31 is released. The closing of contacts 122 of relay 109 and the closing of contacts 141 of relay 139 do not establish circuits since these contacts are in series with open contacts 142 of change-over switch 34.

Just prior to the engagement of the work with the tool, the stop 32 actuates the change-over switch 34 to open the closed contacts 128 thereof and close the open contacts 142. The opening of contacts 128 of change-over switch 34 deenergizes the operating solenoid 125 of rapid-traverse motor control panel 126 disconnecting the rapid-traverse motor from the line and allowing the same to stop. The closing of contacts 142 establishes a circuit from the line L-1 through the stop push button switch 105, line 106, normally open contacts 141 of relay 139, which are now closed, line 143, contact bar 144 of drum controller E, line 145, operating solenoid 146 of relay 147, line 149, closed contacts 142 of change-over switch 34, line 110, closed contacts 111 of travel limit switch 44, line 112, etc., to L-3.

Energization of the operating solenoid 146 of the relay 147 closes the normally open contacts 150, 151 and 152 thereof. This establishes a circuit from the line L-1 through the stop push button switch 105, wire 106, closed contacts 141, line 143, contact bar 144, line 153, normally closed contacts 154 of speed selection switch 42 which also includes normally open contacts 156, line 157, contacts 150, line 158, normally closed contacts 159 of speed selection switch 43 also hav-

ing normally open contacts 162, line 163, contacts 151, line 164, contacts 152, line 165, normally open contacts 166 of speed selection switch 40, which contacts by rearrangement are now closed by the stop 35 on the plate 39, line 107, operating solenoid 108 of relay 109, line 110, closed contacts 111 of travel limit switch 44, line 112, etc., to L-3. This circuit again closes the normally open contacts of relay 109, contacts 122 of which establish a circuit from the line 137, closed contacts 122 of relay 109, line 167, operating solenoid 168 of motor control panel 169, line 170, normally closed contacts 171 of relay 172, line 149, closed contacts 142 of change-over switch 34, line 110, closed contacts 111 of travel limit switch 44, line 112, etc., to L-3.

Energization of the operating solenoid 168 of motor control panel 169 closes the normally open contacts 173, 174, 175 and 176 thereof, connecting the motor 22 to the power lines L-1, L-2 and L-3 in such a manner that the motor rotates at one of its four speeds, which speed is hereinafter referred to as the "first" speed. Simultaneously with the closing of contacts 173, 174, 175 and 176 of motor control panel 169, normally open contacts 177 are also closed. These contacts establish a holding circuit for the operating solenoid 168 of the motor control panel 169 after the speed selection switch 40 is opened upon movement of the stop 35 away from the operating arm thereof. This holding circuit is from the line L-1 through stop push button switch 105, line 106, closed contacts 141 of relay 139, line 143, contact bar 144 of drum controller E, line 153, normally closed contacts 154 of speed selection switch 42, line 157, closed contacts 150 of relay 147, line 158, normally closed contacts 159 of speed selection switch 43, line 163, contacts 151, line 164, contacts 152, line 165, contacts 177, line 167, operating solenoid 168, line 170, normally closed contacts 171, line 149, closed contacts 142, line 110, closed contacts 111, line 112, etc., to L-3.

The operating solenoid 178 of relay 179 is in parallel circuit with the operating solenoid 168 of motor control panel 169 and the relay is actuated simultaneously with the contacts of the motor control panel 169 to open the normally closed contacts 180 thereof. The contacts 180 of relay 179 are in series circuit with the operating solenoids of the motor control panels, hereinafter referred to, which cause the motor 22 to operate at its "third" speed and the opening of these contacts makes certain that these operating solenoids will not be simultaneously energized with the operating solenoid 168 of motor control panel 169 which causes the motor to operate at its "first" speed.

The machine continues to operate with the cut motor rotating at its "first" speed until the stop 36 closes the contacts 181 of the speed selection switch 41, whereupon a circuit is established from the line L-1 through the stop push button switch 105, line 106, closed contacts 141 of relay 139, line 143, contact bar 144 of drum controller E, line 153, normally closed contacts 154 of speed selection switch 42, line 157, closed contacts 150 of relay 147, line 158, normally closed contacts 159 of speed selection switch 43, line 163, closed contacts 151 of relay 147, line 164, normally open contacts 181 of speed selection switch 41, line 182, operating solenoid 183 of relay 172, line 184, normally closed contacts 123 of relay 109 which is now deenergized, line 149, closed contacts 142 of change-over switch 34, line 110, closed contacts

111 of travel limit switch 44, line 112, etc., to L-3. Energization of the operating solenoid 183 of relay 172 opens the normally closed contacts 171 and 185 and closes the normally open contacts 186 thereof. The opening of the normally closed contacts 171 of relay 172 opens the circuit through the operating solenoid 168 of motor control panel 169, disconnecting the connections to the motor 22 by virtue of which it operates at its "first" speed. This also deenergizes the operating solenoid 178 of relay 179 allowing the contacts 180 thereof to close.

The closing of the contacts 186 of relay 172 establishes a circuit through the operating solenoid 187 of motor control panel 188 from the line L-1, through stop push button switch 105, line 106, closed contacts 141 of relay 139, line 143, contact bar 144 of drum controller E, line 153, normally closed contacts 154 of speed selection switch 42, line 157, closed contacts 150 of relay 147, line 158, normally closed contacts 159 of speed selection switch 43, line 163, closed contacts 151 of relay 147, line 164, contacts 186, line 189, operating solenoid 187, line 184, normally closed contacts 123 of relay 109, line 149, closed contacts 142 of change-over switch 34, line 110, closed contacts 111 of travel limit switch 44, line 112, etc., to L-3. Energization of the operating solenoid 187 of the motor control panel 188 closes the normally open contacts 190, 191, 192 and 193 to the power lines in such a manner that the motor continues to operate but at a different speed, herein referred to as the "second" speed. Simultaneously with the closing of the contacts 190, 191, 192 and 193 of motor control panel 188, contacts 194 of the same motor control panel are closed. These contacts are in parallel circuit with the contacts 186 of relay 172 and establish a holding circuit therearound which maintains the operating solenoid 187 of motor control panel 188 energized after the contacts 181 of speed selection switch 41 have opened by the stop 36 moving clear of the actuating arm of said switch. Operating solenoid 195 of relay 196 is in parallel circuit with the operating solenoid 187 of motor control panel 188 and is energized simultaneously therewith to open the normally closed contacts 197 of said relay, which contacts are in series circuit with the operating solenoid 198 of motor control panel 199 by virtue of which the motor is connected to the lines L-1, L-2 and L-3 in such a manner that it operates at a different speed, hereinafter referred to as its "fourth" speed, thus eliminating any possibility of the operating solenoid 198 being simultaneously energized with the operating solenoid 187.

The machine continues to operate with the motor 22 rotating at its "second" speed until the speed selection switch 42 is actuated by engagement of the stop 37 with the operating arm thereof. Actuation of this switch by the stop 37 opens the normally closed contacts 154 and closes the normally open contacts 156 thereof. The opening of the normally closed contacts 154 of speed selection switch 42 breaks the circuit to the operating solenoid 187 of motor control panel 188, deenergizing the circuits by virtue of which the motor operates at its "second" speed. The operating solenoid 195 of relay 196 which is in parallel circuit with the operating solenoid 187 of motor control panel 188 is deenergized at the same time, allowing the normally closed contacts 197 of said relay to close. The closing of contacts 156 of speed selection switch 42 establishes a circuit from the line L-1, through

the stop push button switch 105, line 106, contacts 141 of relay 139, line 143, contact bar 144 of drum controller E, line 153, contacts 156 of speed selection switch 42, line 200, normally closed contacts 201 of motor control panel 188, line 202, normally closed contacts 180 of relay 179, line 203, normally closed contacts 204 of motor control panel 199, line 205, operating solenoid 210 of motor control panel 211, line 212, normally closed contacts 185 of relay 172, line 184, normally closed contacts 123 of relay 109, line 149, closed contacts 142 of change-over switch 34, line 110, closed contacts 111 of travel limit switch 44, line 112, etc., to L-3. The contacts 201 of motor control panel 188, which are now closed, were opened while the motor was operating at its "second" speed, thus preventing any possibility of the operating solenoid 210 of motor control panel 211 being energized simultaneously with the energization of the operating solenoid 187 of the motor control panel 188 by virtue of which the motor is caused to operate at its "second" speed. In like manner the contacts 204, which are now closed, will be open when the motor is operating at its "fourth" speed, thus preventing simultaneous energization of the operating solenoid 210 of motor control panel 211 with the operating solenoid 198 of motor control panel 199.

Energization of the operating solenoid 210 of motor control panel 211 closes the normally open contacts 215, 216, 217, 218 and 219 thereof. The closing of the normally open contacts 218 establishes a circuit from the line 205 through the contacts 218, line 220, operating solenoid 221 of motor control panel 222 to line 212. As previously stated, energization of the operating solenoid 210 of motor control panel 211 closes the normally open contacts 215, 216, and 217 thereof and the energization of the operating solenoid 221 of the motor control panel 222 closes the normally open contacts 223, 224 and 225 thereof. The closing of the contacts 215, 216, 217, 223, 224 and 225 connects the motor 22 to the source of power in such a manner that the motor operates at a different speed than heretofore, which speed is herein referred to as the "third" speed. The closing of normally open contacts 219 of motor control panel 211 establishes a holding circuit around the contacts 156 of speed selection switch 42. This maintains the operating solenoids 210 and 221 of the motor control panels 211 and 222, respectively, energized after the contacts 156 have opened upon movement of the stop 38 away from the actuating mechanism of the speed selection switch 42.

The machine continues to operate with the motor rotating at its "third" speed until the speed selection switch 43 is actuated by engagement of the stop 38 with the operating arm thereon. Actuation of this switch by the stop 38 opens the normally closed contacts 159 and closes the normally open contacts 162 thereof. The closing of the normally open contacts 162 of speed selection switch 43 establishes a circuit from the line L-1 through the stop push button switch 105, line 106, contacts 141 of relay 139, line 143, contact bar 144 of drum controller E, line 153, contacts 154 of speed selection switch 42, line 157, contacts 150 of relay 147, line 158, contacts 162 of speed selection switch 43, line 230, normally closed contacts 231 of motor control panel 169, line 232, normally closed contacts 197 of relay 196, line 229, operating solenoid 198 of motor control panel 199, line 212, normally closed con-

tacts 185 of relay 172, line 184, normally closed contacts 123 of relay 109, line 149, contacts 142 of change-over switch 34, line 110, contacts 111 of travel limit switch 44, line 112, etc., to L-3.

Energization of the operating solenoid 198 of motor control panel 199 closes the normally open contacts 233, 234, 235, and 236, and opens the normally closed contacts 204 thereof. The closing of the normally open contacts 236 establishes a circuit for the operating solenoid 240 of motor control panel 241 from the line 230, through line 238, line 212, etc., closing the normally open contacts 242, 243, 244 and 245. The closing of contacts 233, 234, and 235 of motor control panel 199 and contacts 242, 243, and 244 of motor control panel 241 connects the cut motor 22 to the lines L-1, L-2 and L-3 in such a manner that the motor operates at a different speed, herein referred to as the "fourth" speed. The closing of the normally open contacts 245 of motor control panel 241, which are in parallel circuit with the normally open contacts 162 of speed selection switch 43, maintains closed the circuit to the operating solenoids 198 and 240 of the motor control panels 199 and 241 after the contacts 162 open due to the stop 38 moving away therefrom. The contacts 159 of speed selection switch 43 are in series circuit with the operating solenoid 187 which when energized causes the motor 22 to operate at its "second" speed and the opening of these contacts prevents energization of the operating solenoid 187 simultaneous with the energization of the operating solenoids 198 and 240 of the motor control panels 199 and 241.

Any possibility of the operating solenoid 168 of the motor control panel 169 or the solenoids 210 and 221 of the motor control panels 211 and 222, respectively, being energized simultaneously with the energization of the operating solenoids 198 and 240 of motor control panels 199 and 241, respectively, is prevented in the manner previously pointed out.

The cut motor 22 continues to operate at its "fourth" speed until the travel limit switch 44 is actuated by the stop 45 to open the normally closed contacts 111 thereof and close the normally open contacts 246. The opening of the normally closed contacts 111 of the travel limit switch 44 breaks the circuit to the operating solenoids 198 and 240 of the motor control panels 199 and 241, respectively, whereupon the motor comes to rest. If at any time during the operation of the motor 22 at any of its speeds other than the "first" speed the start button 31 is depressed, the motor will drop back to its "first" speed by virtue of the closing of contacts 122 of relay 109 and the opening of contacts 123 of the same relay. The closing of contacts 122 completes the circuit to the necessary relays, etc., to connect the cut motor 22 to the lines L-1, L-2 and L-3 in such a manner that it operates at its "first" speed, and the simultaneous opening of the normally closed contacts 123 breaks the circuit to all other relays, etc., as will be apparent from the wiring diagram. The cut motor 22 then continues to operate at its "first" speed until one of the speed selection switches 41, 42 and 43 is actuated by its respective stop, whereupon the motor operates at the selected speed and continues its automatic cycle of operation. Any possibility of energizing the operating solenoids 198, 240, 210 and 221 of the motor control panels 199, 241, 211 and 222, respectively, simultaneously with the operating solenoid 187 of motor control panel 188 is prevented by the

normally closed contacts 185 of relay 172, which contacts open along with the closing of contacts 186 which latter contacts energize the operating solenoid 187.

With the work head C at the upper limit of its travel, the work blank is removed and thereafter the work head is returned to its initial position by again depressing the start push button 31. When the start push button switch 31 is now depressed, a circuit is established from the line L-1 through the stop push button switch 105, line 106, start push button switch 31, line 247, operating solenoid 248 of motor control panel 126, line 250, contacts 246 of travel limit switch 44, line 112, etc., to L-3. Energization of the operating solenoid 248 of motor control panel 126 closes the normally open contacts 251, 252, 253 and 254 thereof. The closing of contacts 251, 252 and 253 connects the rapid-traverse motor 30 to the lines L-1, L-2 and L-3 in such a manner that it rotates in the opposite direction, that is, in a direction to lower the work head C. The closing of the normally open contacts 254 of the motor control panel 126 which are in parallel circuit with the start push button switch 31 maintains the circuit to the operating solenoid 248 after the start push button switch has been released. As the work head C moves down, the change-over switch 34 is reset by the stop 32 to again close the contacts 128 and open the contacts 142 thereof. The spindle head continues to move down at a rapid-traverse rate until the travel limit switch 44 is actuated by the stop 32 to open the closed contacts 246 and close the open contacts 111 thereof. The opening of the contacts 246 breaks the circuit to the operating solenoid 248 of motor control panel 126, stopping the rapid-traverse movement. The electrical circuits have now all been returned to their original positions and the cycle of operations can again be completed by depressing the start push button switch 31.

As previously stated, the drum controller E has positions to which it can be turned, designated "first," "second," "third" and "fourth," corresponding with the respective speeds of the cut motor, and when turned to either of these positions the cut motor 22 will operate at the speed selected throughout the entire cutting operation. In all of the above-mentioned four positions, the line 106 is connected to the line 136 by the contact bar 255, thus establishing the same circuits as are established by the contact bar 135 when the drum controller E is set at "auto." When the drum controller E is in "first" position, the line 143 is connected to the line 167 through the contact bar 256. This establishes a circuit from the line L-1 through the stop push button switch 105, line 106, contacts 141 of relay 139, line 143, contact bar 256, line 167, operating solenoid 168 of motor control panel 169, line 170, contacts 171 of relay 172, line 149, contacts 142 of change-over switch 34, line 110, contacts 111 of travel limit switch 44, line 112, etc., to L-3, upon the closing of the contacts 142 of change-over switch 34 which takes place, as previously explained, just prior to the engagement of the work with the cutter. This circuit is maintained throughout the upward continued movement of the work head C as the selection switches for the other speeds are not connected in this circuit. The fact that various selection switches are subsequently actuated has no effect upon the circuit since the circuits for energizing the operating solenoids of other motor control panels are open

as long as the operating solenoid of the motor control panel 169 is energized, as previously explained.

When the drum controller E is turned to "second" position, the contact bar 256 is connected to line 189 in place of line 167. This establishes the operating circuit for solenoid 187 of motor control panel 188 upon the closing of contacts 142 of change-over switch 34 in a manner similar to that previously described with reference to the energization of operating solenoid 168 of motor control panel 169. When the drum controller E is rotated to "third" position, the contact bar 256 is connected to line 200, and, when rotated to "fourth" position, the contact bar is connected to line 230 causing the operating solenoids of motor control panels 211 and 222, and 199 and 241, respectively, upon the closing of contacts 142 of change-over switch 34, causing the cut motor 22 to operate at its "third" or "fourth" speed, as the case may be, in a manner similar to that in which it was caused to actuate at its "first" and "second" speeds when the contact bar 256 is connected to the lines 167 and 189, respectively.

Coolant for the tool is adapted to be supplied by a pump, not shown on the drawings, which pump is driven by an electric motor 257, the operation of which is controlled by a motor control panel 258, the operating solenoid 259 of which is connected in the control circuit previously described in such a manner that the motor 257 operates only while the cut motor 22 is operated. When the operating solenoid 259 of the motor control panel 258 is energized, the normally open contacts 260, 261 and 262 thereof are closed connecting the motor to the lines L-1, L-2 and L-3 causing the same to operate. A snap switch 263 located on the control panel 104 provides means for preventing operation of the motor 257 when it is desired to operate the cut motor 22 without the coolant motor 257. When the switch 263 is closed, a circuit is established from the line 137 through the switch 263, line 265, operating solenoid 259 of motor control panel 258 to line 149. This circuit is in parallel with the operating solenoid 138 of relay 139 when the contacts 142 of change-over switch 34 are closed.

The cut motor 22 is a four-speed alternating current motor of conventional construction. The connections between the motor control panels which actuate the same and the motor are not referred to herein in detail but are well-known in the art and are shown on the wiring diagram. In the wiring diagram, the leads to the motor 22 are designated by the reference characters T-1 to T-14, inclusive. The leads to the motor 30 are designated by the reference characters T-15, T-16 and T-17 and the leads to the motor 257 by the reference characters T-18, T-19 and T-20. The machine can be stopped at any time by depressing the stop push button switch 105. In the embodiment of the invention shown, only two adjustable stops 32 and 45 are employed on the bar 33. In this event the stop 32 performs the dual function of determining the change-over position, that is the position where the rapid-traverse up movement of the work head C stops and the feed movement starts in the cycle of operations, and the down position of the work head C. In other words, the stop 33 actuates the change-over switch 34 and the travel limit switch 44, the latter when the work head C is moving in a downward direction. Alternately a separate adjustable stop may be used to actuate the change-over switch 34, in which event

the sole function of the stop 32 shown would be that of limiting the downward movement of the work head C.

From the foregoing description of the preferred embodiment of the invention it will be apparent that the objects of the invention heretofore enumerated and others have been accomplished and that applicant has provided a new and improved machine of the character described which is simple and economical in construction and operation and which will have a high production. While the preferred embodiment of the invention has been described with considerable detail, it will be apparent that the invention is not limited to the particular construction shown, for example, a cut motor having any number of different speeds may be employed and work of any shape can be turned. It will also be apparent that the cut motor can be operated at its various speeds in any desired sequence by suitably arranging the stops which actuate the speed selecting switches. As shown the cam plate 85 and the plate 39 which carries the stops or trips for the speed selecting switches are separate from each other and detachably connected to the work head C of the machine. Alternatively the plates may be formed integral in which event they would be removable as a unit. In the latter event the stops or trips for the speed selecting switches can be fixed with relation to the cam as there is always a relationship between the trips for the speed selecting switches and the cam which rotates the tool. Other alternative constructions will be apparent to those skilled in the art to which the invention relates and it is my intention to hereby cover all adaptations, modifications and uses of the construction disclosed which comes within the practice of those skilled in the art to which the invention relates.

The phrase "multiple speed electric motor" as used throughout this specification and the following claims, defines an electric motor having a limited number of definite speeds as distinguished from a variable speed electric motor having an infinite number of speeds.

Having thus described my invention, what I claim is:

1. In a machine of the character described, the combination of a frame, a work spindle rotatably supported by said frame, a tool support carried by said frame, a multiple speed alternating current electric motor for rotating said work spindle, means for producing relative movement between said work spindle and tool support in a direction generally parallel to the axis of rotation of the work spindle whereby tooling carried by said tool support is moved axially along a work blank operatively connected to said work spindle, means for causing the tooling to turn portions of different diameter on the work blank as the relative movement between the tool and work is generally parallel to the axis of rotation of the work is effected, an electric control circuit for said motor including means for automatically changing the speed thereof in relation to the diameter of the work being turned, a manually operable device in said control circuit adapted to stop said motor upon being actuated, and means for causing said motor to operate at its slowest speed when again started after being stopped by said device irrespective of the speed at which it was operating at the time said device was actuated.

2. In a machine of the character described, the combination of a frame, a work spindle rotatably

supported by said frame, a tool support carried by said frame, a multiple speed alternating current electric motor for rotating said work spindle, means for producing relative movement between

- 5 said work spindle and said tool support in a direction generally parallel to the axis of rotation of the work spindle whereby tooling carried by said tool support is moved axially along a work blank operatively connected to said work spindle,
- 10 means for causing the tooling to turn portions of different diameter on the work blank as the relative movement between the work and tooling generally parallel to the axis of rotation of the work is effected, an electric control circuit for said motor including means for automatically changing the speed of the motor in relation to the diameter of the blank being turned, a stop switch in said control circuit adapted to stop said motor upon being actuated, means for causing said motor to
- 15 operate at its slowest speed when again started after being stopped by the actuation of said stop switch irrespective of the speed at which it was operating at the time said switch was actuated, a manually operable selecting means in said control circuit adapted to render said means for automatically changing the speed of said motor inoperative and for causing said motor to operate at a selected one of its speeds.

3. In a machine of the character described, the

- 20 combination of a frame, a work spindle rotatably supported by said frame, a tool spindle adapted to carry a disk-like tool having a plurality of radially offset cutting edges along its periphery, means for rotatably supporting said tool spindle by said frame with its axis of rotation at right angles to the axis of rotation of the work spindle and offset therefrom, a multiple speed alternating current electric motor for rotating said work spindle, means for producing relative movement

- 25 between said work spindle and tool support in a direction generally parallel to the axis of rotation of the work spindle whereby a tool carried by said tool support is moved axially along a work blank connected to said work spindle, means for

- 30 rotating said tool spindle during said relative movement between said spindles, an electric control circuit for said motor including means for causing said motor to operate automatically at a plurality of different speeds in a predetermined sequence in relation to the rotation of said tool spindle, a manually operable device in said control circuit adapted to stop said motor upon being actuated, and means for causing said motor to operate at its slowest speed when again started after being stopped by said device irrespective of the speed at which it was operating at the time said device was actuated.

4. In a machine of the character described, the combination of a frame, a work spindle rotatably supported by said frame, a tool spindle adapted to carry a disk-like tool having a plurality of radially offset cutting edges along its periphery, means for rotatably supporting said tool spindle by said frame with its axis of rotation at right angles to the axis of rotation of the work spindle and offset therefrom, a multiple speed alternating current electric motor for rotating said work spindle, means for producing relative movement between said work

- 60 spindle and said tool support in a direction generally parallel to the axis of rotation of the work spindle whereby a tool carried by said tool support is moved axially along a work blank operatively connected to said work spindle, means for
- 65 rotating said tool spindle during said relative movement between said spindles, an electric control circuit for said motor including means for causing said motor to operate automatically at a plurality of different speeds in a predetermined sequence in relation to the rotation of said tool spindle, a manually operable device in said control circuit adapted to stop said motor upon being actuated, and means for causing said motor to operate at its slowest speed when again started after being stopped by said device irrespective of the speed at which it was operating at the time said device was actuated.

- 70 5 In a machine of the character described, the combination of a frame, a work spindle rotatably supported by said frame, a tool spindle adapted to carry a disk-like tool having a plurality of radially offset cutting edges along its periphery, means for rotatably supporting said tool spindle by said frame with its axis of rotation at right angles to the axis of rotation of the work spindle and offset therefrom, a multiple speed alternating current electric motor for rotating said work spindle, means for producing relative movement between said work spindle and said tool support in a direction generally parallel to the axis of rotation of the work spindle whereby a tool carried by said tool support is moved axially along a work blank operatively connected to said work spindle, means for

75 rotating said tool spindle during said relative movement between said spindles, an electric control circuit for said motor including means for causing said motor to operate automatically at a plurality of different speeds in a predetermined sequence in relation to the rotation of said tool spindle, a manually operable device in said control circuit adapted to stop said motor upon being actuated, and means for causing said motor to operate at its slowest speed when again started after being stopped by said device irrespective of the speed at which it was operating at the time said device was actuated.

tive movement between said spindles, an electric control circuit for said motor including means for causing said motor to operate automatically at a plurality of different speeds in a predetermined sequence in relation to the rotation of said tool spindle, a stop switch in said control circuit adapted to stop said motor upon being actuated, means for causing said motor to operate at its slowest speed when again started after being stopped by actuation of said stop switch irrespective of the speed at which it is operating at the time said switch was operated, a manually operable selecting means in said control circuit adapted to render said means for automatically changing the speed of said motor inoperative and for causing said motor to operate at a selected one of its speeds.

5. In a machine of the character described, the combination of a frame, a work head slidably supported by said frame, a work spindle rotatably supported by said work head, a tool spindle adapted to carry a disk like tool having a plurality of radially offset cutting edges along its periphery, means for rotatably supporting said tool spindle in said frame with its axis of rotation at right angles to the axis of rotation of the work spindle and offset therefrom, a multiple speed electric motor for rotating said work spindle, means for moving said work head in a direction generally parallel to the axis of rotation of said work spindle whereby a tool carried by said tool spindle is caused to move axially along a work blank operatively connected to said work spindle, means including a non-uniform cam carried by said work head for rotating said tool spindle at variable speed upon movement of said work head, means for initiating actuation of said motor, and means for automatically changing the speed of said electric motor in a predetermined variable sequence but in timed

relation to the rotation of said tool spindle, said last mentioned means including electric switching mechanism which when successively actuated causes said motor to operate at a different one of its speeds and adjustable means carried by said work head for actuating said electric switching mechanism.

6. In a machine of the character described, the combination of a frame, a work head slidably supported by said frame, a work spindle rotatably supported by said work head, a tool spindle adapted to carry a disk-like tool having a plurality of radially offset cutting edges along its periphery, means for rotatably supporting said tool spindle in said frame with its axis of rotation at right angles to the axis of rotation of the work spindle and offset therefrom, a multiple speed alternating current electric motor for rotating said work spindle, means carried by said frame for changing the speed of said electric motor, said means including electric switching mechanism which when successively actuated causes said motor to operate at different speeds, means for moving said work head in a direction generally parallel to the axis of rotation of said work spindle whereby a tool carried by said tool spindle is caused to move axially along a work blank supported in said work head and operatively connected to said work spindle, means including a cam for rotating said tool spindle in predetermined relation to the movement of said work head, a plurality of adjustable members carried by said work head for actuating said electric switching mechanism in a variable predetermined sequence, and means for rendering said electric switching mechanism inoperative and for causing said motor to operate at any selected one of its speeds.
